Primary Examiner — Jonathan J Han(74) Attorney, Agent, or Firm — Schwabe, Williamson & Wyatt, P.C.(57) CLAIM

I claim the ornamental design for a shoe, as shown and described.

DESCRIPTION

FIG. 1 is a photographic front bottom perspective view of an embodiment of a shoe; midsole and outsole, showing my new design;

FIG. 2 is a bottom view thereof;

FIG. 3 is a right side view thereof;

FIG. 4 is a left side view thereof;

FIG. 5 is a front view thereof; and,

FIG. 6 is a rear view thereof.

The broken lines depict features of the shoe that form no part of the claimed design.
